US00D774759S

(12) United States Design Patent (10) Patent No.: US D774,759 S
Beilman et al. (45) Date of Patent: * Dec. 27, 2016

(54) COSMETIC CASE

(71) Applicants: Debra L. Beilman, Aventura, FL (US);
Florencia Crosa, North Miami, FL (US)

(72) Inventors: Debra L. Beilman, Aventura, FL (US);
Florencia Crosa, North Miami, FL (US)

() Term: 15 Years

(21) Appl. No.: 29/530,065

(22) Filed: Jun. 12, 2015

(51) LOC (10) Cl. 03-01

(52) U.S. Cl.

USPC D3/284; D3/288; D3/296; D3/901

(57) CLAIM

The ornamental design for a cosmetic case, as shown and described.

DESCRIPTION

FIG. 1 is a front perspective view illustrating my design for a cosmetic case;

FIG. 2 is a front elevation view thereof;

FIG. 3 is a left side view thereof;

FIG. 4 is a top view thereof;

FIG. 5 is a right side view thereof;

FIG. 6 is a bottom view thereof;

FIG. 7 is a rear view thereof;

FIG. 8 is a front perspective view in a partially open orientation thereof; and,

FIG. 9 is a front perspective view in a completely open orientation thereof.

The broken lines illustrate stitching and form no part of the claimed design.

1 Claim, 9 Drawing Sheets
